UNITED STATES PATENT OFFICE.

JOSE AURELIO HIDALGO, OF LOS ANGELES, CALIFORNIA.

DESIGN FOR A DANCING ANIMAL TOY.

60,542.

Specification for Design.

Patented Mar. 7, 1922.

Application filed September 13, 1921. Serial No. 500,453. Term of patent 3½ years.

To all whom it may concern:

Be it known that I, JOSE AURELIO HIDALGO, a citizen of the Republic of Mexico, residing at Los Angeles, in the county of Los Angeles and State of California, have invented a new, original, and ornamental Design for a Dancing Animal Toy, of which the following is a specification, reference being had to the accompanying drawing, forming a part thereof.

The figure is a perspective view of a dancing animal toy, showing my new design.

I claim:

The ornamental design for a dancing animal toy, as shown.

JOSE AURELIO HIDALGO.

Witnesses:

EDMUND A. STRAUSE,
JAMES H. PETTIBONE.
